UNITED STATES PATENT OFFICE.

HARRY E. DOERR, OF ST. LOUIS, MISSOURI, ASSIGNOR TO SAMSON CAR COUPLER COMPANY, OF NEW YORK, N. Y., A CORPORATION OF NEW YORK.

CAR-COUPING.

1,138,198.

Specification of Letters Patent.

Patented May 4, 1915.

Application filed February 5, 1914. Serial No. 816,801.

To all whom it may concern:

Be it known that I, HARRY E. DOERR, a citizen of the United States, residing at St. Louis, Missouri, have invented a certain new and useful Improvement in Car-Couplers, of which the following is a full, clear, and exact description, such as will enable others skilled in the art to which it appertains to make and use the same.

10 This invention relates to car couplers, and particularly to couplers of the type shown in United States Patent No. 902,616, dated November 3, 1908, in which the knuckle is provided with a pair of wings that embrace the drawhead and which enter notches in the locking pin when the coupler is in uncoupled position.

15 The main object of my invention is to provide a car coupler of the type mentioned which comprises an efficient means of simple construction for preventing the locking pin from being withdrawn completely from the head during the operation of arranging said pin in position to release the knuckle or permit the knuckle to open.

Another object is to provide a car coupler in which the knuckle is equipped with a device that limits the movement of the locking pin and prevents it from becoming accidentally displaced when said pin is being shifted into an inoperative position preparatory to releasing the knuckle. And still another object is to provide a car coupler which is so designed that the knuckle effectively holds the locking pin in the drawhead, and prevents accidental displacement of same when the knuckle is in its closed and open positions. Other objects and desirable features of my invention will be hereinafter pointed out.

Figure 1 of the drawings is a top plan view of a car coupler constructed in accordance with my invention; Fig. 2 is a side elevational view of said coupler; Fig. 3 is a vertical sectional view taken on the line 3-3 of Fig. 1; Fig. 4 is a perspective view of the locking pin; and Fig. 5 is a perspective view of the pivotally mounted retaining device for the locking pin.

50 Referring to the drawings which illustrate the preferred form of my invention, A designates the drawhead of the coupler, B designates the pivotally mounted knuckle which is provided with a pair of wings 1

and 2 that embrace the drawhead, and C designates the locking pin which is provided with notches or recesses 1^a and 2^a that receive the wings 1 and 2 on the knuckle and thus permit the knuckle to be opened after the locking pin C has been raised so as to bring the notches or recesses 1^a and 2^a in same into alignment with the wings on the knuckle.

The reference character D designates the pivotally mounted retaining device on the head that moves into engagement with a shoulder on the locking pin C when said pin is raised or moved upwardly so as to retain said pin in its elevated position until the wings on the knuckle enter the notches 1^a and 2^a in the locking pin.

My invention consists in providing the coupler with means for preventing the locking pin C from being drawn out of the head A accidentally when said pin is raised or moved upwardly to release or unlock the knuckle B, and in the preferred form of my invention as herein illustrated, said means consists of a laterally projecting device or stop 3 on the top wing 1 of the knuckle, shown in broken lines in Fig. 1, that enters an elongated vertically-disposed slot 4 in the locking pin C when the knuckle is locked in its closed position by the pin C. When the locking pin C is raised upwardly, preparatory to opening the knuckle B, the projection 3 on the top wing of the knuckle strikes against a shoulder 5 on the locking pin, preferably formed by the bottom wall of the recess or notch 1^a in said pin and thus limits the upward movement of the pin, thereby preventing the locking pin from being completely withdrawn from the head A of the coupler.

When the knuckle is in its closed position, as shown in Fig. 1, the locking pin C cooperates with the wings on the knuckle to securely lock the knuckle in its closed position, and the projection 3 on the top wing of the knuckle which enters the elongated slot 4 in the locking pin prevents said locking pin from being withdrawn accidentally from the head. When the knuckle B is in its open position the wings thereon are positioned in the notches 1^a and 2^a of the locking pin and thus prevent the locking pin from being withdrawn from the head. Consequently, the knuckle of my improved

coupler effectively holds the locking pin in the head and prevents accidental withdrawal of same when the coupler is in coupling or uncoupling position; or, in other words, my improved coupler is so designed that the knuckle or parts on the knuckle co-operate with the locking pin to retain it in the head and prevent it from being withdrawn from the head when the knuckle is in its closed position and in its open position.

My improvement adds practically nothing to the cost of manufacturing the coupler because the stop on the knuckle that limits the upward movement of the locking pin consists of a device that is preferably formed integral with the knuckle and the slot in the locking pin which receives said device is formed during the operation of casting the locking pin. Furthermore, my improvement does not comprise any detachable parts that are apt to work loose and become lost when the coupler is loose.

While I prefer to arrange the stop for the locking pin on the top wing of the knuckle, I do not wish it to be understood that my invention is limited to a coupler of this exact construction for my broad idea consists in a car coupler provided with a knuckle which comprises means for limiting the upward movement of the locking pin and preventing it from being withdrawn from the head acci-

dently when said locking pin is being moved into position to release the knuckle.

Having thus described my invention, what I claim as new and desire to secure by Letters Patent is:

In a car coupler, a head, a locking pin arranged in said head in such a manner that it can move in a vertical direction only, said pin being provided with a pair of cut-out portions arranged one above the other, a knuckle pivotally mounted in said head and provided with a pair of tails arranged one above the other that lie wholly without said head and which co-operate with cut-out portions on said pin to hold said pin in its raised position when the knuckle is in its open position, and a lateral projection on the uppermost tail that cooperates with a vertically-disposed slot formed in said pin above the uppermost cut-out portion thereof when the knuckle is in its closed position, said projection being adapted to contact with the lower edge of the uppermost recess when the locking pin is raised so as to prevent the complete withdrawal of said pin.

In testimony whereof I hereunto affix my signature in the presence of two witnesses, this 31st day of January, 1914.

HARRY E. DOERR.
